UNITED STATES PATENT OFFICE.

JOSEPH A. BOGDONAWICH, OF RINGTOWN, PENNSYLVANIA.

VEGETABLE CUTTER.

Application filed January 14, 1928. Serial No. 246,888.

This invention relates to vegetable cutters and it is an object of the invention to provide a device of this kind particularly intended for use in slicing potatoes in a manner to materially reduce the cost of labor and to minimize any possible injury to the operator.

Another object of the invention is to provide a device of this kind comprising a rotating cutting element together with a chute for delivering a potato or other vegetable to said element to be cut, said rotating cutting element being mounted in a manner permitting the same to be adjusted as desired toward or from said feeding chute.

A further object of the invention is to provide a cutter of this kind provided with means to facilitate the discharge of the cuttings and particularly in a manner whereby the same may be readily collected within a suitable receptacle, thus materially increasing the efficiency of the device.

The invention consists in the details of construction and in the combination and arrangement of the several parts of my improved vegetable cutter whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in perspective of a vegetable cutter constructed in accordance with an embodiment of my invention;

Figure 2 is a fragmentary view in side elevation illustrating the means herein disclosed for clamping the device in applied position, an associated table or other support being shown in section;

Figure 3 is a fragmentary vertical sectional view taken through the upper portion of the device as illustrated in Figure 1;

Figure 4 is a horizontal sectional view taken through the upper portion of the structure in Figure 1;

Figure 5 is a view in elevation of the cover member as herein embodied;

Figure 6 is a view in rear elevation of the cutting or slicing element as herein employed;

Figure 7 is a detailed sectional view illustrating the mounting of the cutting blade with respect to a slot in an associated disc.

As disclosed in the accompanying drawings, 1 denotes a base plate having associated therewith a well known type of clamping means, generally indicated at 2, whereby the device in its entirety may be properly engaged with a marginal portion of a table or other desired support. Extending upwardly from the plate 1 and disposed transversely thereof is a loop frame 3 of requisite dimensions, said frame 3 being brazed or otherwise fixed to the plate 1. This frame 3 is of a design to provide the straight side portions *a* although this is not entirely essential to the efficiency of the device.

Arranged fore and aft of the frame 3 are the horizontally disposed and substantially U-shaped brackets 5 and 6, the side members 5' of the forward bracket 5 being herein disclosed of a length greater than the side members 6' of the bracket 6. The extremities of the side members 5' and 6' of both of the brackets are provided with the outwardly disposed and substantially perpendicularly related feet 7 which have direct contact with the portions *a* of the frame 3 adjacent the upper ends of said straight portions and through which are directed the headed members or bolts 8 also disposed through the portions *a* of the frame 3 whereby, through the medium of the coacting nuts 9 engaged with the bolts 8, the brackets 5 and 6 are firmly engaged with and supported by the frame 3. This mounting of the brackets 5 and 6 arrange the same substantially in alignment or coplanar one with the other.

The intermediate members 5^a and 6^a of the brackets 5 and 6 provide mountings for the shaft 10 arranged at substantially the longitudinal centers of said intermediate members 5^a and 6^a and bridging the space therebetween. Mounted upon the shaft 10 and at a point substantially between the portions *a* of the frame 3 is a disc 11 provided therethrough with a pair of substantially opposed and radially directed slots 12 each of which having associated therewith a cutting blade 14 whereby, upon proper application of a potato or other vegetable, the disc 11 upon its rotation will result in an effective slicing of the vegetable.

The disc 11 is freely mounted upon the

shaft 10 but its peripheral portion is fixed, by the bolts 15 or otherwise as may be preferred, to the inwardly disposed feet 16 carried by the outer extremities of the arms 17. 5 These arms 17 are carried by a hub disc 18. This hub disc 18 is spaced a desired distance from the disc 11 and the arms 17 are disposed on a requisite incline to compensate for such spacing. Threaded upon the shaft 10 at opposite sides of the hub disc 18 and in clamping engagement therewith are the nuts 19 whereby this hub disc 18 is fixed to the shaft 10 for rotation therewith. These nuts 19 also provide a means whereby the hub 10 disc 18 together with the disc 11 may be conveniently adjusted in a direction lengthwise of the shaft 10 as the necessities of practice may require.

Freely mounted upon the shaft 10 and interposed between the outer nut 19 and the intermediate portion 6^a of the bracket 6 is a sleeve or bushing 20 and also mounted upon the shaft 10 but outwardly of this intermediate portion 6^a is a second sleeve or bushing 21. 25 An operating handle 22 has threaded engagement with the portion of the shaft 10 outwardly of the sleeve 21 which snugly engages between said portion 6^a and the applied handle member 22.

30 The outer end portions of the side members 5 of the bracket 5 have secured thereto the upwardly and inwardly inclined arms 23, the upper end portions of which being continued by the upwardly inclined parallel arms 24 disposed in the same general direction as the shaft 10. Interposed between these arms 24 is a feeding chute 25, the side marginal portions of which being secured to the arms 24 through the medium of the bolts 26 or the like. The mounting of the feeding chute 25 is such as to have its inner or lower end terminate in relatively close proximity to the disc 11 so that the knives carried by the disc will have proper working 35 engagement with the potato or other vegetable placed within the feeding chute. The cuttings made by the knives of the disc 11 are adapted to be discharged within a suitable receptacle or container placed adjacent to the device and this collection of the cuttings is assured by a depending chute 27 of a scoop like type having its upper portions anchored, as at 28, to the side members 5 of the bracket 5, said fastening members 28 being also included in the anchoring means for the arms 23. This depending chute 27 when applied has its face opposed to the intermediate portion 5^a of the bracket 5.

60 A cover member C is disposed over the upper end of the depending chute 27 and is of such configuration as to readily extend over the disc 11 and provide sufficient clearance for the requisite admission of the vegetable to be cut or sliced. The outer end portion of the cover C is provided with a de-

pending flange 29 having in its marginal portion a cut out portion or recess 30 to compensate for the shaft 10 while the inner end portion of the cover C at the opposite side thereof is provided with the depending feet 31 having open slots 32. Through the medium of these open slots 32 the feet 31 are readily engaged with the headed members or bolts 8 outwardly of the applied nuts 9 and held in such engagement by the wing nuts 33 or the like. By this means, the cover C is effectively maintained in applied or working position yet can be readily removed when desired.

From the foregoing description it is thought to be obvious that a vegetable cutter constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A vegetable cutter comprising an upstanding frame including side members, anchoring means for said frame, brackets secured to the side members of the frame and positioned fore and aft thereof, a shaft rotatably supported by said brackets, a cutting element rotating with the shaft, upwardly disposed arms carried by one of the brackets, and a feed chute supported by said arms and disposed toward the cutting member.

2. A vegetable cutter comprising an upstanding frame including side members, anchoring means for said frame, brackets secured to the side members of the frame and positioned fore and aft thereof, a shaft rotatably supported by said brackets, a cutting element rotating with the shaft, upwardly disposed arms carried by one of the brackets, a feed chute supported by said arms and disposed toward the cutting member, and a chute depending from said brackets, said chute receiving cuttings made by the cutting element.

3. A vegetable cutter comprising an upstanding frame including side members, anchoring means for said frame, brackets secured to the side members of the frame and positioned fore and aft thereof, a shaft rotatably supported by said brackets, a cutting element rotating with the shaft, upwardly disposed arms carried by one of the brackets, a feed chute supported by said arms and disposed toward the cutting member, a chute depending from said brackets,

said chute receiving cuttings made by the cutting element, and a cover disposed over the upper portion of the depending chute and the cutting element.

5. A vegetable cutter comprising an up-standing frame including side members, anchoring means for said frame, brackets secured to the side members of the frame and positioned fore and aft thereof, a shaft 10 rotatably supported by said brackets, a cutting element rotating with the shaft, upwardly disposed arms carried by one of the brackets, a feed chute supported by said arms and disposed toward the cutting member, a chute depending from said brackets, 15 said chute receiving cuttings made by the cutting element, a cover disposed over the upper portion of the depending chute and the cutting element, and means for connecting said cover with the frame whereby the frame supports said cover.

20 5. A vegetable cutter comprising an up-

standing frame including side members, anchoring means for said frame, brackets secured to the side members of the frame 25 and positioned fore and aft thereof, a shaft rotatably supported by said brackets, a cutting element rotating with the shaft, upwardly disposed arms carried by one of the brackets, a feed chute supported by 30 said arms and disposed toward the cutting member, said cutting member comprising a disc freely mounted on the shaft and provided with cutting knives, a hub disc arranged on the shaft at a point spaced from 35 the first named disc, means for connecting said hub disc to the shaft, arms carried by the hub disc and extending to the peripheral portion of the first disc, and means for connecting said arms to the first disc. 40

In testimony whereof I hereunto affix my signature.

JOSEPH A. BOGDONAWICH.
